UNITED STATES PATENT OFFICE

JAMES H. HOLDEN, OF BRENTWOOD, THOMAS O'BRIEN, OF SHARON, AND JOSHUA C. WHETZEL AND RUFUS E. ZIMMERMAN, OF PITTSBURGH, PENNSYLVANIA, ASSIGNEES TO AMERICAN SHEET AND TIN PLATE COMPANY, OF PITTSBURGH, PENNSYLVANIA, A CORPORATION OF NEW JERSEY

METHOD OF REMOVING, PURIFYING, AND RECOVERING OIL FROM TIN PLATE

Application filed June 15, 1926. Serial No. 116,130.

This invention relates to methods of removing, purifying and recovering the oil from tin plates after they are tinned, and more particularly to a novel method in which 5 the oil is removed from the plates and purified and then returned for use in the tin pot.

Heretofore the freshly tinned plates have generally been passed from the tin pot 10 through a "branner" in which the plates were scoured with bran, which absorbed the oil and polished the plates. This method was costly because of the large quantities of bran used, and also because the oil was lost. 15 The present method removes the oil by washing the plates in an alkaline water solution and forms an alkaline palm oil-in-water emulsion, which emulsion is then treated to recover a water-in-palm oil emulsion, and this second emulsion is then treated 20 to recover pure dry palm oil suitable to be returned to the tin pot for use.

In the drawings:

Figures 1 and 2 combined show a sectional elevation of a tinning machine, washing machine, and branner, as used in carrying out 25 the steps of this method.

Figure 3 is a sectional side elevation of the apparatus used to separate and recover the 30 oil from the emulsion discharged from the washer.

In carrying out this invention, black or 35 untinned plates are fed into the flux side of a tin pot A, where they are engaged by a pair of feed rolls 2 and fed downwardly through a body of flux 3 and into the molten tin 4. As the plates are fed through the tin 4, they are engaged by a second pair of feed rolls 5 and fed through the opening 6 40 into the oil or exit side of the pot A. As the plates enter the oil side of the tin pot A, they engage the guide 7, and are turned upwardly so as to be engaged by the exit or feed-out rolls 8 which feed the plates out 45 of the tin pot through a body of palm oil 9 and also squeeze off any surplus tin. The plates pass from the rolls 8 into the bite of a pair of feed rolls 10 which feed the plates upwardly so that they will fall onto 50 an inclined feed-table 11 from which the

plates will move onto a conveyer-table B, and be fed into a washing-vat or tank C.

The vat or tank C is adapted to be filled with a hot soda ash or other alkaline solution, and to be constantly supplied with 55 water from a pipe 12 at the rate of from twenty to twenty-five gallons per hour, and to have additions of soda ash or other alkali at the rate of four-tenths of a pound per hour.

The plates enter the vat or tank C from the table 11 through a pair of guides 14 and are engaged by pairs of scrubbing or scouring rolls 15 and 16. The lower roll of the pair of rolls 15 is of smaller diameter 65 than the upper roll and has a fabric or rubber surface covering 17, while the upper roll of the pair of rolls 16 is of smaller diameter than the lower roll and has a fabric or rubber surface covering 18. The smaller 70 rolls of the pairs of rolls 15 and 16 are adapted to have a greater surface speed than the larger rolls so that the smaller rolls will rub or scour the plates to wash off the oil and form an emulsion of the oil and water. 75

Other pairs of rolls 19, 20, and 21 are arranged above the level of the washing solution in the vat or tank C, and serve to feed the washed plates from the tank and to squeeze off and dry and also to polish the 80 plates.

The lower roll of the pair of rolls 19, the upper roll of the pair of rolls 20, and the lower roll of the pair of rolls 21 are each provided with a fabric or rubber surface covering 22, and the rolls of each of the above pairs of rolls have a differential surface speed, so that the liquid from the tank C will not only be squeezed off the plates but the rolls will have a rubbing action on the plates which serves to dry the plates and also to polish the plates.

The plates may, if desired, be passed from the rolls 21 to stock as a finished article, but are preferably passed from the rolls 21 onto 95 a conveyer-table 23, which conveys them to a branner 24 of standard design, which is filled with a quantity of bran and has a series of pairs of rolls 25. The rolls of each of the pairs of rolls 25 have a differ- 100

ential surface speed so as to scour or rub the plates, and this scouring action together with the bran serves to remove any oil which might still remain on the plates and to highly polish the surfaces of the plates.

5 The branner 24 is also provided with two pairs of feed-out rolls 26 which feed the polished plates onto a magnetic feed-out roll 27, which in turn delivers the plates onto a buggy 28 or the like, which will convey them to any suitable point such as to stock or a point of storage.

10 By washing the plates in the vat or tank C, the oil is removed prior to the entrance 15 of the plates into the branner 24. Therefore, the bran may be used for a considerable length of time in the branner, while heretofore the bran had to be continually changed. This saving in the amount of bran 20 used is a considerable item.

15 The primary function of the washing of the plates in the vat or tank C is to remove the oil from and clean the tin plate and to form an emulsion from which the oil 25 may be recovered; but another and important result is accomplished at the same time, in that the oil is at least partly purified in the tank C.

20 The oil removed from the plates in the vat or tank C is emulsified by the action of the scrubbing rolls 15 and 16 in the presence of the hot alkaline solution. The oil is finely dispersed and thus put in an ideal condition for the removal of any impurities 35 soluble in the alkaline wash water. Other impurities, insoluble in water, may also be removed from the oil during emulsification and suspended in the water. The finely divided condition of the oil is not lost until 40 the oil is separated from the water as later described.

45 The most harmful impurity in the oil is flux or zinc chlorid. It is a very active agent in causing the decomposition of palm oil, and experience has shown that a large amount of the zinc chlorid is removed from the oil prior to the separation of the oil from the water in the emulsion formed in the tank C. The removal of the zinc chlorid 50 greatly improves the quality of the oil for tin pot use. The zinc chloride and other soluble compounds are washed from the oil and dissolved in the water in the tank C, and are then carried by the water content 55 of the emulsion and removed as the water is removed from the emulsion.

60 At the same time that the chlorid and other soluble impurities are removed from the oil, quantities of the cleaning mixture or soda ash, dirt from the water supply, sodium salts, etc. are picked up by the oil. These added impurities are not objectionable, since they are easily removed in the later centrifugal purification step, to be described.

65 It will be noted from the above that the washing of the tin plate serves as an important step in the purifying of the oil, as well as cleaning the tin plate, since soluble impurities which would not be removed later 70 are removed from the oil by this operation as above described, thereby permitting the oil to be returned to the pots in better quality than would be otherwise possible.

75 The alkaline palm oil-in-water emulsion from the tank C flows through an overflow-pipe 29 into a drain-pipe 30, thence to a trough 31, from which it flows through a pipe 32 to the heating and mixing chamber 33 of a treatment-tank D. The tank D is 80 divided by transverse walls 34 and 35 into the heating and mixing chamber 33, a separating chamber 34^a and an oil receiving chamber or sump 35^a. A steam-line 36 extends into the tank D, and has one branch 85 37 extending onto and forming a coil 38 on the inclined top face of the wall 35, thence over and into the mixing and heating chamber 33, as at 39, where it terminates and supplies live steam to the emulsion 90 therein to heat and agitate the emulsion. Another branch 40 of the steam-line 36 extends down into the oil chamber or sump 35^a where it terminates in a heating coil 41.

95 An acid-tank 42 containing sulfuric acid is provided above the tank D, and a pump 43 is provided for delivering measured quantities of the acid through a conduit 44 to the heating and mixing chamber 33 of 100 the tank D.

105 The treatment tank D serves two purposes. It separates the major portion of the water content from the oil of the emulsion so that the water may be dumped or drained into drains or sewers without danger of stoppage of the sewers and contamination of streams. It also permits for formation of a new emulsion in the form of a 110 alkaline palm oil-in-water emulsion. The treatment of the alkaline palm oil-in-water emulsion in the tank D is continuous with a constant discharge of substantially oil-free water.

115 The emulsion entering the tank D has approximately the following composition:

	Per cent
Sodium carbonate	0.2
Palm oil	2.1
Water	97.7

120 The overflow or water discharged from the tank D contains little or no oil, approximately 0.3 per cent. sodium sulfate, and approximately 0.1 per cent. free sulfuric acid. The water-in-oil emulsion formed by the gravity separation of the water content from the original oil-in-water emulsion after said oil-in-water emulsion has been broken down in the tank D, contains about 60 per cent. water which is later removed. Experi-

ence has shown that it is easily possible to recover from 98 to 99 per cent. of the oil from the emulsion entering the tank D.

As the emulsion flows into the chamber 33 of the treatment-tank D, a small quantity of sulfuric acid from the tank 42 flows through the conduit 44 and mixes with the emulsion. The quantity of sulfuric acid entering the oil-in-water emulsion in the chamber 33 of the treatment tank D is regulated so as to provide a concentration of approximately .01 per cent. in the water separated out of the emulsion in the separating chamber 34^a. Live steam is delivered into the mixture of acid and emulsion in the chamber 33, from the pipe 39 which heats the mixture and accelerates the reaction, and also serves to thoroughly mix the emulsion and acid. The reaction of the acid and emulsion is favored by high temperature and good agitation. A temperature of 140 degrees Fahrenheit is generally maintained in the chamber 33. The effect of the acid is to break down the alkaline palm oil-in-water emulsion so that the water and oil may be readily separated. The quantity of emulsion and acid mixture builds up in the chamber 33 and flows over the wall 34 into the separating-chamber 34^a where it is allowed to separate by gravity, the oil rising and the water settling and being discharged through a stand-pipe 45 arranged to maintain a water level closely adjacent the top of the wall 35 so that the oil rising to the top of the water will flow over the wall 35 into the oil chamber or sump 35^a. The oil rising through the water of the broken down oil-in-water emulsion will pick up or combine with some of the water and form a water-in-oil mixture. Experience has shown that a water level approximately 1½ inches below the top of the wall 35 is satisfactory.

The oil which rises to the surface in the separating chamber 34^a as a water-in-oil mixture gradually builds up as a frothy mixture and after reaching a few inches in thickness overflows into the oil chamber or sump 35^a. This flow is aided by the application of heat from the coil 38 on the top of the wall 35. The oil-chamber or sump 35^a is of sufficient capacity to permit a considerable accumulation of the water-in-oil mixture, and it is not necessary that the subsequent operations be carried on continuously, although it is entirely possible to make the entire process continuous.

The results obtained by breaking down the emulsion with sulfuric acid and separating the oil from the water of the emulsion may be accomplished by a number of other means, but probably less efficiently. The treatment of the emulsion may be carried on entirely as a batch proposition, without continuous separation; also other more com-

plicated methods might be used. Acids other than sulfuric may be used to break the oil-in-water emulsion. Experience has thus far shown that commercial sulfuric acid of 60 degrees Baumé strength is the most economical to use. However, almost any other acid or acid mixture, such as waste pickle liquor, may be used as reagents to break the emulsion.

After the water-in-oil mixture has collected in the chamber or sump 35^a, it is pumped out through a conduit 46 by a pump 47 and discharged into a screen 48. The mixture flows through the screen 48 while any large particles of tin or other foreign matter remain on the screen. The water-in-oil mixture flowing through the screen is collected in a vat 50 having a steam coil 51 therein. A pipe 52 leads from the vat 50 to a pump 53 which draws the mixture from the vat 50 and forces it through a coil 54 in a heating drum 55. The water-in-oil mixture is heated in the coil 54 so as to vaporize the water content thereof and the coil discharges the oil and vapor mixture into the lower end of a stack 56. Steam is supplied to the drum 55 through an inlet pipe 57 at approximately 140 pounds per square inch pressure, and flows from the drum through a pipe 58 to a steam-trap or the like (not shown).

The oil and vapor mixture discharged from the coil 54 into the stack 56 is separated, the vapor being picked up by the draft of air in the stack and the oil flowing down into the storage-vats or tanks 59 and 60 which are provided with steam-coils to maintain the oil at approximately 300 degrees Fahrenheit. The heated oil from the tanks 59 and 60 is adapted to be passed through a pipe 61 to a standard form of centrifuge 62 and have the solid foreign matter separated therefrom. The finally purified oil is then discharged into a tank or vat 63 and is ready to be returned in any desired manner to the oil side of the tin pot A for use on other tin plate.

The water-in-oil mixture pumped from the sump 35^a contains a large amount of water, some sulfate picked up in the treatment-tank D, and incidental dirt and foreign matter picked up at various stages in the process. Notwithstanding the increase of certain impurities, an important step in the purification has taken place in the removal of the large amount of chlorid by the washing fluid. The chlorid is not readily removed in the subsequent operations, while the other impurities are removed more or less completely after the oil is dried.

As the water-in-oil mixture is discharged on the screen 48 any large particles of foreign matter are removed. The screened mixture is then collected in the vat 50 and

preheated by the steam coil 51. The pre-heated mixture is then pumped from the vat 50 and forced through the coil 54 in the heating drum 55 where it is heated to approximately 300 degrees Fahrenheit so as to cause the water content of the mixture to vaporize. Higher or even lower temperatures may be used to vaporize the water content of the mixture, or the coil 54 may be heated directly by free flame in an open furnace. However, experience has indicated that much more trouble may be expected in obtaining uniformity of operations if an open flame is used.

15 The water content of the water-in-oil mixture is vaporized in the passage of the mixture through the coil 54 and the water vapor and oil are separated where the mixture of oil and water vapor is forced into the 20 up-flowing draft of air in the stack 56, thus drying the oil. The vapor will be carried up through the stack by the stack-draft, while the dried oil will run down through the stack and be collected in the tank or 25 vat 59. Baffles and additional heat may be used in the stack if desired or necessary. By a proper control of temperature, air flow and pumping of the water-in-oil mixture, the water passes up the stack 56 as steam or 30 vapor, and only a trace or less than 0.1 per cent. of water remains in the oil. Experience has shown that the whole operation may be controlled by the temperature at 35 the exit end of the drier-coil 54. If this temperature is maintained at 300 degrees Fahrenheit or above and there is a proper flow of air through the stack 56, the water will be removed practically completely.

40 The dried oil is passed from the tank or vat 60 through the high speed centrifuge 62. The centrifuge 62 serves to throw out a considerable proportion of the ash forming and other foreign matter from the oil as a sludge, and lowers the viscosity of 45 the dried oil to approximately the same value as when it left the tin pot A. The oil returned to the tin pot contains a much smaller amount of chlorid and probably less ash and other foreign matter in general 50 than the oil removed from the tin plates in the washer C.

55 The dried oil is fed to the centrifuge 62 at a high temperature for efficient sludge removal. This sludge removal is favored by a small rate of flow through the centrifuge and a high oil temperature. Experience has shown that a temperature of approximately 300 degrees Fahrenheit and a flow of forty gallons per hour is very efficient.

60 In addition to the purification of the tin pot oil taking place in the centrifuge 62, a valuable by-product is obtained in the form of the sludge removed from the oil, which is deposited in the bowl of the centrifuge and recovered. This sludge is re-

65 moved from the centrifuge and taken to the scruff furnace of the mill where the tin content is recovered as a tin-bearing ash, and the value of the tin thus recovered is sufficient to cover a large proportion of 70 the expenses chargeable to this oil treating process.

75 From the above, it will be readily understood that we have developed a complete process whereby the oil is removed from the tin plates, purified and recovered, with a minimum of expense and labor.

80 While we have shown and described certain specific apparatus used to carry out our process together with specific steps, it will be understood that we do not wish to be limited to these details, since various other forms of apparatus may be used to carry out the steps of our novel method, and various modifications in the method steps may be 85 made, such as changes in temperatures, rates of flow, and the like without in any way departing from the scope of our invention as defined in the appended claims.

89 We claim:

1. The method of purifying and recovering palm oil from an alkaline palm oil-in-water emulsion formed by washing palm oil from tin plate and the like with an alkaline water solution, which consists in collecting the emulsion, breaking down the emulsion by adding acid to said collected emulsion, separating the major portion of the water content of the broken down emulsion by gravity while the oil content of said emulsion rises through and floats on said water in the form of water-in-oil mixture, then collecting said water-in-oil mixture, heating said water-in-oil mixture, so as to vaporize the water content thereof, then discharging the oil and water vapor mixture formed by vaporizing the water content of the water-in-oil mixture, into the path of a body of up-flowing gaseous fluid so as to permit the water vapors to be carried upwardly with the gaseous fluid while the oil falls through said fluid by gravity substantially free from all water, then collecting said oil, and finally separating all foreign solid matter from said collected oil.

115 2. The method of purifying and recovering palm oil from an alkaline palm oil-in-water emulsion formed by washing palm oil from tin plate and the like with an alkaline water solution, which consists in collecting the emulsion, breaking down the emulsion by adding acid to said collected emulsion, separating the major portion of the water content of the broken down emulsion by gravity while the oil content of said emulsion rises through and floats on said water in the form of a water-in-oil mixture, then collecting said water-in-oil mixture, heating said water-in-oil mixture so as to vaporize the water content thereof,

120

125

130

then discharging the oil and water vapor mixture formed by vaporizing the water content of the water-in-oil mixture into the path of a body of up-flowing gaseous fluid 5 so as to permit the water vapors to be carried upwardly with the gaseous fluid while the oil falls through said fluid by gravity substantially free from all water, then collecting said oil, and finally centrifuging the 10 oil to remove ash-forming materials, tin particles and other foreign matter from the oil.

3. The method of purifying and recovering palm oil from an alkaline palm oil-in-water emulsion formed by washing palm oil from tin plate and the like with an alkaline water solution, which consists in collecting the emulsion, breaking down the emulsion by adding acid to said collected 15 emulsion, separating the major portion of the water content of the broken down emulsion by gravity while the oil content of said emulsion rises through and floats on said water in the form of a water-in-oil mixture, then collecting said water-in-oil mixture, heating said water-in-oil mixture so as to vaporize the water content thereof, then discharging the oil and water vapor mixture formed by vaporizing the water content 20 of the water-in-oil mixture into the path of a body of up-flowing gaseous fluid so as to permit the water vapors to be carried upwardly with the gaseous fluid while the oil falls through said fluid by gravity substantially free from all water, then collecting 25 said oil, and finally centrifuging the oil to remove any ash-forming materials, tin particles and other foreign matter as a sludge, collecting the oil for reuse, and collecting 30 the sludge to recover the tin content thereof.
